CONCRETE FINISHING TOOL

William S. Haivala and Paul E. Griggs, Wichita, Kans.,
assignors to Haivala Concrete Tools, Inc., Wichita,
Kans.

Filed Jan. 13, 1975, Ser. No. 540,641

Term of patent 14 years

Int. Cl. D8—05

U.S. Cl. D8—45

FIG. 1

FIG. 2

FIG. 3

FIG. 4

FIG. 5

FIG. 1 is a perspective view of a concrete finishing tool incorporating our new design;

FIG. 2 is a top plan view with the bottom plan view not being shown since it is totally planar;

FIG. 3 is a right end elevational view;

FIG. 4 is a left end elevational view; and

FIG. 5 is a side elevational view of the tool with the opposite side being a mirror image.

We claim:

The ornamental design for a concrete finishing tool, as shown and described.
